United States Patent Office.

WILLIAM J. JOHNSON, OF NEWTON, AND HENRY A. HILDRETH, OF LOWELL, MASSACHUSETTS.

Design No. 4,163, dated June 21, 1870.

DESIGN FOR A WIRE BROILER.

The Schedule referred to in these Letters Patent and making part of the same.

We, WILLIAM J. JOHNSON, of Newton, and HENRY A. HILDRETH, of Lowell, in the State of Massachusetts, have invented and produced a new and original Design for Wire Broilers, the nature of which is fully represented in the accompanying drawing, to which reference is made,

A B being the upper and lower handles ;
C D, the upper and lower gratings ;
E F, the hinges ; and

G, the slide clasp, the same being for the form or shape.

What we claim is—

The design for a wire broiler, as shown and described.
